J. T. COWLES

COUNTERBALANCE LADDER CONSTRUCTION

Filed Jan. 4, 1923

Inventor
John T. Cowles,
By Sprinkle, Hopkins & McNeil Atys.

UNITED STATES PATENT OFFICE.

JOHN T. COWLES, OF CHICAGO, ILLINOIS, ASSIGNOR TO J. T. COWLES & COMPANY, A CORPORATION OF ILLINOIS.

COUNTERBALANCE-LADDER CONSTRUCTION.

Application filed January 4, 1923. Serial No. 610,566.

To all whom it may concern:

Be it known that I, JOHN T. COWLES, a citizen of the United States, and resident of Chicago, county of Cook, and State of Illinois, have invented certain new and useful Improvements in Counterbalance-Ladder Constructions, of which the following is a specification.

My invention relates to counter-balance ladders and refers more particularly to fire escapes and other ladders, which are subject to atmospheric conditions.

In the construction of counter-balance ladders heretofore employed it has been customary to fasten the counter-balance arm to the ladder by rivets or bolts passing through the arm and a portion of the ladder, with the result that the adjoining surfaces can not be painted from time to time to preserve the metal parts. Such failure to preserve has resulted in premature rusting along the contacting faces or surfaces of the arm and ladder requiring frequent repairs and replacements. My invention overcomes this objection in that the counter-balance arm is secured to the ladder in spaced relation by members having curved surfaces so as to reduce to a minimum the area of contact between the members and the ladder.

An object of my invention is to provide a counter-balance ladder construction to prevent rusting of adjacent parts and premature destruction of the same.

Another object is to provide a counter-balance ladder construction wherein the counter-balance arm may be attached to the ladder in such manner as to reduce the area of contact to a minimum.

A further object of the invention is to provide a counter-balance ladder construction wherein the arm may be applied to the ladder in such manner as to reduce the contacting surfaces therebetween to a minimum, thus enabling the application of preservatives, such as paint, to the greater portion of the surfaces of said ladder and arm for the prevention of rust.

A still further object of the invention is to provide a counter-balance arm for application to pivoted structures wherein the contacting surfaces may be reduced in area with the parts arranged to receive ready application of preservatives.

Generally speaking, I carry out the pre-

ferred embodiment of the invention by securing a counter-balance arm to a ladder or similar structure, which arm is arranged in parallel spaced relation with respect to the ladder and is attached in such position by members, certain of which have curved surfaces for clamping against the ladder structure, with certain of the members provided with means for attachment to the arm.

The above recited and other objects will be apparent from the following description and drawings and will be particularly pointed out in the appended claims.

In the drawings, Fig. 1 is a side elevation of the invention as applied to a fire escape ladder.

Fig. 2 is a front elevation of the arrangement of Fig. 1.

Fig. 3 is an enlarged section taken on line 3—3 of Fig. 1, and

Fig. 4 is an enlarged section taken on line 4—4 of Fig. 3.

It has been the practice in the past to attach a counter-balance arm to a ladder, especially a fire escape ladder, along the side of the ladder proper, with the result that rust takes place and the parts quickly rust and become unsafe.

In the drawings, I have shown a platform 5 of a fire escape system secured by supports 6 to the wall of the building in any desirable manner. Extending downwardly from the platform 5 is a section 7 including steps. At the lower end of section 7 a pivot 8 is provided, which is secured by means of supporting rods 8^a to suitable overhead connections. The ladder A is pivoted at 8 and is adapted to swing about the pivot into operative and inoperative positions for purposes well understood.

The ladder A comprises side members formed of parallel flat strips 9 and 10 joined together at suitable intervals by short pieces 11, the treads being formed by cross members 12 suitably secured in the sides of the ladder. A hand rail 13 carried by supports 14 secured to the sides of the ladder is provided. In fire escape constructions the weight or counter-balance is disposed on the opposite side of the pivot from the ladder. In the present instance the weight 15 is secured to the outer end of an arm 16, which arm extends on the opposite side of the pivot 8 and is secured to the ladder A in the following manner.

Referring to Fig. 3, it will be observed that the arm 16 is channel shaped in form, which channel comprises flanges 17 and 18. The arm 16 is disposed in edgewise relation 5 with respect to the side members 9 and 10 of the ladder and is spaced therefrom a slight distance. For securing the arm 16 to the ladder I provide a plurality of clamping members 19 and 20, using as many sets of 10 the clamping members as may be desirable. The members 20 are cylindrical in shape and are made as shown in Figs. 3 and 4 of the drawings. The members 19 comprise two portions, a lower portion 19^a which is cylindrical and which is in size and shape the same as the members 20; a second portion 19^b, which is reduced in diameter to form a bolt, the outer end of which is threaded as at 21. The members 19 and 20 are provided 15 with registering apertures 22 and 23 through which a bolt 24 is passed for clamping the members 19 and 20 on opposite sides of the members 9 and 10 of the ladder side. Such construction is shown in Fig. 20 3. The flanges 17 and 18 of the counter-balance arm are provided with registering apertures 25 and 26 through which the reduced or bolt portions 19^b of the clamping members 19 are passed, and a nut 27 is then 25 applied to the upper or threaded end of each of the members 19^b. It will be observed that the contact of the members 19 and 20 with the flat members 9 and 10 of the ladder side is the contact of a curved or cylindrical 30 surface against a flat surface, the relationship of which is clearly shown in Fig. 4. Such construction permits the ready application of paint or other preservative to the metal parts of the ladder and arm and the 35 ready application of paint or the like to all but a very small part of the area between the clamping members 19 and 20. Such a construction affords the exclusion of rust from 40 between the adjacent surfaces as it permits 45 ready application of preservatives to substantially all of the exposed surfaces.

In the drawings I have shown three sets 50 of clamps 19 and 20 supporting the arm 16 above the upper edge of the side member 9 of the ladder. It is within the contemplation 55 of the invention to support the arm 16 below the ladder side, if desirable. It may readily be observed that this construction eliminates areas within which moisture may 60 gather and oxidation result. A ladder constructed in accordance with my invention will outlast many times a similar ladder arranged alongside the side members of the ladder 65 where flat surfaces are in contact with other flat surfaces.

While I have described more or less precisely the details of construction of my invention, I do not wish to be understood as 70 limiting myself thereto, as I contemplate

changes in form and in the proportion of parts and the substitution of equivalents, as circumstances may suggest or render expedient, without departing from the spirit of my invention. 70

I claim:

1. A device of the class described, including in combination a pivoted structure and a counter-balance arm therefor, said arm being secured to said structure in parallel spaced relation, means for securing said arm along said structure comprising members having curved surfaces for contacting portions of the structure, certain of said members having portions adapted to engage and hold said arm in operative position, and means co-operating with said curved surface members for maintaining the same in contact with the said structure. 80

2. A counter-balance ladder, including in combination a counter-balance arm, said arm being secured to said ladder in edgewise relation and attached to one of the sides of said ladder, means for holding said arm in position comprising a plurality of sets of clamps, said clamps having cylindrical portions for bearing against the ladder side with certain of said members provided with extensions for engaging said arm, and means co-operating with said cylindrical portions for securing the same in clamping engagement against the ladder side. 90

3. A counter-balance ladder having an arm secured to the ladder by a plurality of sets of clamps, said sets of clamps having curved surfaces disposed on opposite portions of a side member of the ladder with means passing through said members for clamping the same against said ladder, certain of said clamping members being provided with portions engaging said arm for retaining the same in position on the ladder. 100

4. In a device of the class described, in combination a pivoted structure, a counter-balance arm therefor, and means for securing said arm on to said structure including members having curved surfaces engaging said arm and adapted to be clamped against flat surfaces of said structure for reducing 110 the area of contact therewith. 115

5. In a device of the class described in combination with a pivoted structure, a counter-balance arm therefor, said arm being secured above said structure in parallel exposed relation, means for securing said arm to said structure comprising members having cylindrical surfaces for contacting portions of said structure, certain of said members having reduced portions adapted 120 to engage and hold said arm in operative relation, and bolts extending through said members for clamping said members to said structure. 125

6. In a device of the class described, in 130

combination with a pivoted structure, a counter-balance arm therefor, and means for securing said arm on said structure comprising a plurality of cylindrical members, 5 certain of said members having reduced portions for engaging said arm, said members having their cylindrical surfaces clamped against the flat surface of said structure.

In testimony whereof I have signed my 10 name to this specification on this 29th day of December, A. D. 1922.

JOHN T. COWLES.
